UNITED STATES PATENT OFFICE.

RICHARD MARX, OF PHILADELPHIA, PENNSYLVANIA, ASSIGNOR TO JOHN B. STETSON,
OF ASHBOURNE, PENNSYLVANIA.

SAFETY-RAZOR.

1,169,665.

Specification of Letters Patent. Patented Jan. 25, 1916.

Application filed January 9, 1913. Serial No. 740,985.

To all whom it may concern:

Be it known that I, RICHARD MARX, a citizen of the United States, residing in Philadelphia, Pennsylvania, have invented 5 certain Improvements in Safety-Razors, of which the following is a specification.

One object of my invention is to provide a safety razor of the utmost simplicity of construction, which in addition to being 10 relatively inexpensive to manufacture, shall be provided with a relatively uncomplicated device for positioning and releasing the razor blade.

Another object of the invention is to provide 15 a razor whose blade holder shall consist of but two relatively movable parts, one of which is formed to hold the blade in the proper position, while the other is being applied.

These objects and other advantageous 20 ends I secure as hereinafter set forth, reference being had to the accompanying drawings, in which,

Figures 1 and 2 are respectively a front 25 and a side elevation of a safety razor constructed according to my invention; Figs. 3 and 4 are respectively an inverted plan and a rear elevation of the razor; Fig. 5 is a plan of the razor showing the blade retaining plate partly removed; Fig. 6 is a front elevation showing the handle with the guard plate and a blade mounted on the latter; Fig. 7 is a plan of one of the razor blades; 30 Figs. 8 and 9 are plans illustrating modified forms of the blade and guard plate, and, Fig. 10 is an enlarged side elevation of the guard shown in Fig. 9 illustrating a 35 blade in position thereon.

In Figs. 1 to 7 of the above drawings, 1 40 represents a handle to the top of which is rigidly fixed a blade receiving guard plate 2 of rhomboidal outline and inclined forwardly as well as downwardly toward one side. Said blade holder at its forward edge 45 is provided with a series of guard teeth 3 projecting in planes substantially parallel to a plane passing through the center line of the handle 1. As shown in Fig. 2, this guard plate is upwardly concave and as 50 shown in Fig. 5 at its rear edge is provided with two upwardly turned lugs 4.

The blades employed with my razor have a substantially rhomboidal outline, as indicated at 5 in Fig. 7 and in addition to 55 lugs 6 projecting at opposite ends of one

of its edges, each blade has on the same edge a rearward projection 7 which is undercut at its ends as indicated at 8. This projection is of such a length as to closely fit between the lugs 4 of the supporting 60 guard plate 2 and as shown in Figs. 5 and 6, said lugs are beveled or slightly inclined at their adjacent ends to fit into the undercut portions 8 in such manner as to prevent the withdrawal of a blade in a plane substantially parallel to and immediately adjacent that of the guard plate.

For retaining the plate in operative position I provide a cover plate 9 having an elongated rhomboidal outline and provided 70 at each end with a pair of clips 10 whose ends are bent toward each other in such manner as to frictionally engage the under side of the guard plate and also strike the lugs 6, although with the projection 7 75 and its co-acting holding lugs 4 which likewise serve to limit the upward movement of said cover plate 9, said lugs 6 may be omitted without departing from my invention.

When it is desired to mount a blade in the holder, it is laid on the upper face of the guard plate 2 with its projection 7 extending between the lugs 4 so that it is held 80 from moving in a plane substantially parallel to that of said plate. While so positioned, the retaining plate 9 is applied by engaging one of its clips 10 with one end of the guard plate, thus bringing said first named plate into the position shown in Fig. 90

5. Thereafter it is moved from this position into a position in which it lies fairly over the guard plate with its sides parallel to the sides thereof as well as to those of the blade and with the second clip 10 frictionally holding to the under side of the guard plate. In order to remove a blade, the operator places his first and second fingers against the rear face of the guard plate on either side of the handle and with his 95 thumb in engagement with the retaining plate 9, slides this latter off of the blade and out of engagement with the guard plate, thus permitting the blade to be taken from the latter by an upward movement.

100 With a razor constructed as above described, the blade may be conveniently applied to or removed from the holder without danger of the operator being cut since after said blade has once been placed in the 110

position shown in Fig. 6, with its projection 7 held between the lugs 4, it cannot easily be dislodged but is properly held in the correct position until the retaining plate 5 is applied as above described. If desired I may provide the guard plate 2 with two small projections 11 as indicated in Fig. 5 immediately adjacent the two ends of that edge having the guard teeth 3, the purpose 10 of these being to provide a two point support for the blade body in the vicinity of its cutting edge. It will be noted that the projection 7 of the blade has a width substantially equal to the thickness of the lugs 4 15 of the guard plate 2; it being immaterial whether said projection fits between two lugs on said plate or whether, as shown in Figs. 8 and 9, said blade 5^a has a recess 7^a, one edge of which is undercut at the ends for 20 the reception of a single lug 4^a on the guard plate 2^a.

From Fig. 10 it will be seen that when the parts are assembled, the ends of the cutting edge of the blade rest upon the endmost 25 guard teeth 3^a of the series and these are not only slightly longer than the teeth 3 between them but are curved upwardly so that said cutting edge is spaced away from and unsupported by said intermediate teeth. The 30 projections 11, however, engage the blade body just back of the cutting edge so as to positively support it when it is pressed toward the plate 2 by the retaining plate 9. Obviously the lengths of these projections 35 may be very accurately fixed during manufacture to secure the desired adjustment of the razor.

I claim:—

1. The combination in a safety razor, of a 40 handle; a guard plate mounted thereon having guard teeth at one edge, two portions of the opposite edge of said plate being turned up and having their adjacent ends beveled; a blade having a projection from the edge 45 opposite its cutting edge provided with undercut ends fitting the beveled ends of the turned up portions on the guard plate and also having end projections; with a cover

plate for holding the blade in place having end clips engaging the blade projections and 50 abutting on the turned up portions of the guard plate.

2. The combination in a safety razor, of a handle; a guard plate mounted thereon having guard teeth on one edge and a portion of 55 its opposite edge turned up; a blade formed to have holding engagement with said turned up edge portion and provided with laterally projecting lugs at its opposite ends; with a cover plate having clips at its 60 ends formed to frictionally engage the guard plate and abutting on the laterally projecting lugs of the blade when the latter is in its operative position.

3. A razor blade having an undercut projection on its rear edge and formed with projecting lugs on the rear portions of its 65 opposite ends respectively.

4. A razor blade of rhomboidal outline having a projection at its back edge formed 70 with undercut ends; with lugs at the opposite ends of the blade adjacent its rear edge.

5. The combination in a safety razor, of a handle; a guard plate mounted thereon having guard teeth at one edge and provided 75 with two upturned portions at its opposite edge; a blade abutting said upturned portions and provided with a projection extending between the same, said blade also having projections at its ends adjacent its rear 80 edge; with a cover plate slidably engaging the blade and having end clips respectively engaging opposite ends of the guard plate, said cover plate also abutting on the upturned edge portions of the guard plate and 85 the clips positively engaging the end projections of the blade to hold the same in place.

In testimony whereof, I have signed my name to this specification, in the presence 90 of two subscribing witnesses.

RICHARD MARX.
